UNITED STATES PATENT OFFICE.

CLYDE F. McCANN, OF SAN FRANCISCO, CALIFORNIA.

MACHINE SWITCHING SYSTEM FOR TELEPHONE EXCHANGES.

Application filed November 4, 1926. Serial No. 146,175.

This invention pertains to a new method of machine switching for telephone systems. The object of the invention is to provide a simple, inexpensive, reliable and quick acting machine switching system for telephone systems.

The present systems in use for machine switching are, as far as is known, all operated upon the step by step method or principle. That is, the calling subscriber, upon raising his hook and dialing a number say 1234, sets certain apparatus or machinery in motion, which hunts first thru the thousands, then the hundreds, then the tens and finally the units until the required number is found, and the connection is made. Upon the establishment of a connection and conversation between the two subscribers, certain switches and multiple banks of contacts are held up and used during the length of the conversation or "holding time". The cost of the present machine switching installation therefore, varies not only in proportion to the number of subscribers, and number of calls per maximum busy hour, but also roughly in proportion to the average "holding time" of the individual subscribers.

A method of machine switching then which would eliminate the use of any expensive apparatus during the holding time of a subscriber's connection would be quite a step in advance of present methods as far as cost at least is concerned. This I firmly believe the present invention will do. Further, comparatively little multiple wiring and banking is required in this system,—an additional great saving in cost of installation.

Now a brief and general description of this invention. First, in this system, the jack of each subscriber is made on the design of a key, working on the principle of combinations of numbers. In an exchange having numbers of four digits, say numbers 1000 to 9999, there are nine digits in the thousands, ten digits in the hundreds, ten in the tens, and ten in the units, or 39 digits in all. From combinations of these 39 digits, 9000 possible telephone numbers can be made. Substitute now for these 39 digits 39 magnetically operated rods, against which rest lugs of 9000 subscribers' jacks, each jack having four lugs corresponding to that particular subscriber's number. Now if a calling subscriber can dial a number of four successive digits, store up

the same, and then instantly operate four corresponding magnetically controlled rods, plugging the called subscriber's jack and his own to a common line, he will have made a direct telephone connection. This is what is done in the present invention, and therefore a suitable name for the same would be "The key system of machine switching for telephone exchanges".

In this system then, briefly, a subscriber removes his receiver from the hook and dials a set of numbers which are recorded in his individual unit at the exchange office. Upon completion of his dialing and the line being clear, these numbers are switched upon corresponding magnets, which operate attached rods and plug the called subscriber's jack and at the same time the caller's jack unto a set of battery bus bars, accomplishing a direct connection. The battery bus bars and connected jacks are then automatically raised to an out of the way position, and magnets and all other apparatus restored to normal, so that another connection of any other two subscribers can be quickly made. The two connected subscribers can then communicate with each other for any length of time, and at minimum installation cost, for the only apparatus used during the length of a conversation or "holding time" are the two jacks and a pair of battery bus bars. Upon hanging up of the receivers, the jacks drop back to normal.

It will be noted in this system, that each subscriber has attached to his line an inexpensive number recording unit. This means that any time spent in dialing a number does not hold up anyone else, or tie up the main switching apparatus, so that the key switching machinery is occupied at all times in constantly plugging in jacks and making connections.

Now referring to the drawings—

Figures 1, 2 and 3 show the outline of the key system of machine switching with sufficient detail equipment for connecting two subscribers. Fig. 1 shows the subscriber's local phone and dial unit connected to the individual recording and switch equipment at the switching station. Fig. 2 is a duplicate of Fig. 1 showing another subscriber's equipment. Each subscriber in the system has a similar equipment. Fig. 3 shows the key switching bank common to all the subscribers which has a jack and key for each one. Fig.

3 is drawn in perspective for the sake of clearness. The wiring from Fig. 1 and Fig. 2 can be readily traced to Fig. 3.

Let us now trace the circuits and operation in detail, and assume that subscriber A, Fig. 1 desires to make connection with subscriber B, Fig. 2. The subscriber's house phone equipment needs no detailed explanation, being standard for most automatic systems.

10 Subscriber A lifts receiver (1) from hook (2) thereby establishing a direct current loop thru dial 3, transmitter 4, hook switch 2, inductance 5, via subscriber's line 6 and 7 to switching station. The lines 6 and 7 enter 15 the ringer switch unit 8 and are attached respectively to blades 9 and 10. This ringer switch disconnects the ringer from the circuit and also the recording unit at the proper time, and will be more fully described later.

20 Normally the blades of the ringer switch are held against contacts 11 and 12 by the tension of spring 13. The blades also make sliding contact with lugs 14 and 15. The circuit then, from subscriber's wire 6 goes thru blade 25 9 of the ringer switch, thru lug 14, wire 16, magnet 17, wire 18, to the plus terminal of battery 19 and finally to ground. Tracing the circuit from subscriber's wire 7, it goes thru blade 10, lug 15, wire 20, the primary 30 21 of transformer 22, wire 23, magnet 24 and to ground. A direct current circuit or loop has been made. One result of this is that magnet 17 is energized and pulls down on iron core 27, causing switch blades 9 and 10 to 35 break contact with lugs 11 and 12 which function in the ringer circuit. The blades are pulled down far enough by magnet 17 however, to make contact with lugs 25 and 26. The above operation is a preparatory one and 40 has no immediate effects.

Another result of the making of this loop is that magnet 24 is energized and brings relay switch 28 into contact with terminal lug of wire 29, sending a current from battery 45 plus thru wire 29 to magnet 30 and to ground. Now magnet 30 has a core 31 which is attached to lever 32 whose pivot axis is 33. Pivoted at the upper end of lever 32 is an idler roll 34 whose other pivot point is on arm 35 50 which swings about axis 36. Behind and close to roll 34 is regulating ratchet 37 and recording ratchets 38, 39 and 40. Just behind these ratchets is the power friction roll 41. This roll is being driven at a uniform 55 speed by a motor and turns in such a direction as to move the ratchets upward when they press against it.

Now referring again to magnet 30, this having been energized, pulls core 31 outward, 60 thus acting on lever 32 and forcing idler roll 34 inward. This action pinches the ratchets between rolls 34 and power roll 41 so that the ratchets will move upward when released by their pawls. This also is a preparatory action. 65

One more effect produced by the making of the loop or circuit by the subscriber is to act upon transformer 22. Transformer 22 has a primary 21 and a secondary 42, from which lead wires 43 and 44 to shaded core 70 magnet 45. Magnet 45 operates on pawl 46. Consider what happens when the subscriber raises his hook switch. A direct current is sent thru the primary winding 21 of the transformer 22. The expanding magnetic flux of 75 this current cuts the secondary winding 42 causing a brief flow of current thru lines 43 and 44 and magnet 45. Magnet 45 being energized, draws the lower end of pawl 46 toward it releasing regulating ratchet 37 80 which moves upward one-half notch until caught by the tooth on the upper end of pawl 46. Upon secession of the flow of current, magnet 45 loses its flux and the pawl 46 being pulled back by its spring, allows the regulating ratchet to raise one-half notch higher, or a total of one full notch. The lug 47 of 85 regulating ratchet 37 has now come into sliding contact with stationary lug 48 connected by wire 49 to magnet 50 whose other terminal 90 is grounded. The making of this contact between the lugs 47 and 48 completes a circuit via wire 20, wire 51, ratchet 37, lug 47, lug 48, wire 49, magnet 50 to ground, thus energizing magnet 50 with direct current. Magnet 50 95 therefore draws pawl 52 toward its core, which releases the engaged tooth on ratchet 38 and allows it to raise one-half notch, in which position it is held by the retaining action of the upper tooth of pawl 52 100 and the continued holding of magnet 50. This one-half notch raise of ratchet 38, however, has not yet brought its lug 53 in contact with lugs 54.

To summarize briefly the action so far,— 105 subscriber A lifts receiver 1 from hook switch 2 completing an electrical circuit with battery 19 as source of current supply. This energized magnet 17 of ringer switch 8 accomplishing a preparatory switching movement. Magnet 24 is also energized, causing relay switch 28 to energize magnet 30 which 110 forces roll 34 against ratchets 37, 38, 39 and 40, which in turn press against power roll 41. These four ratchets then tend to raise 115 when released from their pawls. Also the making of this loop circuit acts on transformer 22 and magnet 45 causing ratchet 37 to raise one notch and make contact with lug 48. This in turn energizes magnet 50, causing ratchet 38 to raise one-half notch. The 120 above action simply prepares the subscribers individual apparatus at the switching station for receiving the numbers to be dialed by the calling subscriber. The subscriber then 125 is now ready to dial a number.

These sketches Figs. 1, 2 and 3 show an equipment for numbers of three digits, that is numbers from 111 to 999.

Let us now assume that subscriber A, Fig. 130

1 desires to call a subscriber whose phone number is 222, and that this subscriber to be called is B, Fig. 2. He proceeds to dial the first number #2 on dial 3. The details of the 5 dial are not shown because this is standard equipment. The dialing he does by placing his finger in dial hole #2 and turns the dial to the stop lug and then releases it. The dial then automatically returns to normal, meaning 10 while breaking the loop circuit twice, and therefore making it twice. Let us see now the results produced in subscriber A's equipment at the station.

In the first place the quick break and make 15 of the circuit has not opened the relay switch 28 on account of the shaded core or shorted ring of magnet 24 which holds the magnetic flux thru short interruptions of the current. Therefore roll 34 remains in operation during 20 the dialing ready to raise the ratchets. Now consider the effect of dialing the first digit upon regulating ratchet 37 which is operated by magnet 45.

During the break and make operation of 25 the line circuit thru primary winding 21, an alternating current is induced in the secondary circuit which energizes magnet 45 and thus draws over pawl 46, and holds it there on account of the shaded core of magnet 45. 30 This raises the ratchet 37 one half notch though it is still in contact with lug 48. Now, however, when the dial is back to normal, and a steady flow of current is in the line circuit, the current ceases in the secondary 35 circuit, and magnet 45 releases pawl 46 advancing the ratchet 37 another one-half notch into contact with lug 55, and clear of lug 48, thus preparing the circuit for the operation of ratchet 39 on the dialing of the 40 second digit. Meanwhile, magnet 50 has acted on pawl 52 to raise recording ratchet 38 two whole notches so that its lug 53 now rests against #2 bar of 54. In other words #2 of the hundreds has been recorded. The 45 banks of bars shown in cross-section in the upper part of Fig. 1 and Fig. 2 are the same in both and common to all the subscribers.

Subscriber A next dials the second digit of 50 the number 222. The circuit for magnet 57 has been prepared via ratchet 37, lug 55, and wire 56. In dialing, the subscriber breaks and makes the circuit twice on magnet 57, causing pawl 58 to allow the recording ratchet 39 to raise two notches, and bring lug 59 to rest against bar #2 of the tens bank 60. Therefore digit #2 of the tens has been recorded. As the current in the subscriber's loop becomes steady again, regulating ratchet 55 37 raises one-half notch more so that lug 47 makes contact with lug 61 thus energizing magnet 63 via wire 62 and preparing ratchet 40 for recording the last digit.

Subscriber A now dials the last digit #2 60 of the number 222, which causes magnet 63 to operate pawl 64, raising ratchet 40 two

notches so that lug 65 rests against #2 bar of units bank 66. The number 222 has now been recorded.

Subscriber A can do nothing further now to get his party, so that the remaining action 70 at the switching station must automatically connect subscriber A with subscriber B. Also subscriber B must be rung, this ringing to be audible to subscriber A, and the ringer must be disconnected from the circuit when 75 B lifts his receiver. These automatic operations are accomplished as below.

When the loop current becomes steady after the dialing of the last digit of the called 80 number, ratchet 37 operated by magnet 45 raises one-half notch and its lug 47 makes contact with lug 67 sending the loop current via wire 68 to magnet 69. Magnet 69 thus energized has sufficient power to pull up switch 70. Now each subscriber has a similar switch. The object of this switch is to put battery voltage via the recording bars into the proper jack magnets shown in Fig. 3 and thus release two subscribers' jack arms 85 and plug the two jacks to common bus bars. Now this is done almost instantly, but only one connection can be made at one time on one jack bank as of Fig. 3. Therefore, it is necessary to arrange that only one calling subscriber's jack magnet switch such as 70 will 90 go in at one time. This is accomplished by the "hold back" wire 71 which is common to all the subscribers' jack-magnet switches, and is shown common to Fig. 1 and Fig. 2. Whenever any subscriber's jack-magnet switch is in, the "hold-back" wire 71 becomes charged plus from battery 19.

Let us assume for the moment that subscriber B's switch is in and line 71 charged plus. Then direct current goes from line 71 thru lug 72, thru switch 73 to "hold back" magnet 74 and to ground. The "hold back" magnet 74 is so wound as to produce a magnetic field tending to minimize the field of magnet 69. Therefore as long as magnet 74 is energized from wire 71, magnet 69 is prohibited from drawing up switch 70. As soon as "hold-back" wire 71 is clear of voltage, however, magnet 69, when energized will 100 throw up switch 70.

Coming back to subscriber A's call now, we left off at the point where magnet 69 was energized from wire 68. With line 71 cleared, magnet 69 throws switch 70 up. As the switch rises, arm 75 strikes switch 73 and disconnects line 71 from hold-back magnet 74. The object of this is to keep the subscriber's own voltage from energizing magnet 74 and throwing out his switch 70. Next the blades of switch 70 are all thrown in, blade 76 to ratchet 38, blade 77 to ratchet 39 and blade 78 to ratchet 40. Blade 80 puts plus voltage on "hold-back" wire 71, prohibiting other subscribers' switches from being thrown in at 110 that instant. Blade 79 puts voltage on wire 115 120 125 130

81 which goes to subscriber A's individual jack magnet shown in Fig. 3. Ratchets 38, 39 and 40 have now put plus voltage on wires 82, 83 and 84, which go to the corresponding 5 jack magnets of the key controlled plugging bank Fig. 3. Let us now trace these circuits to Fig. 3.

Fig. 3 is a perspective view of the key 10 jack-plugging machine which plugs together any two subscribers coming into that exchange. If the telephone traffic is too great, a multiple of this plugging bank can be installed. Fig. 3 shows an outline of the plugging machine, and subscribers A and B's keys, 15 jack arms and jacks in detail. A row of plugging solenoids 85 plug in the jack of any called subscriber.

The numbers possible to call lie between 111 20 and 999. There are a total of twenty-seven plugging solenoids, nine in the hundreds, nine in the tens and nine in the units. If number say 179 is called, solenoids #1 hundreds, #7 tens, and #9 of the units are energized 25 and pull to the right their cross bars, allowing the key and jack arms of subscriber 179 to move in the same direction and plug jack 179 into the battery bus bars. In the figure, only six plugging solenoids are shown, or numbers 1 and 2 each of the hundreds, tens 30 and units. (a) Shows subscriber A's key jack equipment, and (b) shows subscriber B's equipment.

Let us continue now with subscriber A's 35 call #222 to subscriber B. Lines 82, 83 and 84 have been made live with plus battery voltage, thus energizing solenoids 86, 87 and 88 respectively, whose other terminals are grounded. Now each solenoid has a sliding iron core rod, the right end of which is attached to a compression spring bearing 40 against stationary plate 89, and the left end attached to a horizontal cross bar. Thus solenoid 86 operates bar 90, solenoid 87 bar 91, and solenoid 88 bar 92.

45 Examining subscriber B's jack equipment (b), we find that this consists of, first a solid T shaped unit made up of a vertical plate 93, rigidly attached to a horizontal arm or rod 94, terminating in a head 95 which carries a 50 horizontal ring 96. Rigidly attached to plate 93 is subscriber B's key solenoid 97. The core rod 98 of this solenoid is attached firmly to key 99 whose three lugs bear against bars 90, 91 and 92 respectively. The key 99 is slideable 55 with relation to plate 93. The pull of tension spring 100 on core rod 98 normally holds key 99 at rest against pins 101 and 102 which are attached to plate 93. Tension spring 103 attached to arm 94 and plate 89 keeps the lugs 60 of key 99 pressed against bars 90, 91 and 92. Held loosely in the spring ring 96 of rod head 95 is subscriber B's jack 104. This jack is equipped with four clips, the inner two for battery connection, and the outer two for ringer connection. From jack 104 leads cable 65

105 containing wires 106 and 107 from the battery clips, and wires 108 and 109 from the ringer clips.

Returning now to the making of subscriber A's call to subscriber B. Plugging solenoids 70 86, 87, and 88, being energized, pull down bars 90, 91, and 92 away from the lugs of key 99. This allows spring 103 to pull rod 94 to the right plugging in the clips of jack 104 into horizontal bus bars 110. The inner clips 75 make contact with the inner battery bus bars, and the outer clips with the outer ringer bus bars.

At the same time that subscriber B's jack 80 plugs in, subscriber A's jack is being plugged in. In Fig. 1 wire 81 has already been energized by A's switch 70. Wire 81 leads to key solenoid 111 of jack unit (a). Solenoid 111 being energized, pulls its core rod 112 and key 113 to the left against the tension of spring 114 and away from pins 115 and 116. This action pulls the lugs of key 113 away from bars 117, 118 and 119, and allows tension spring 120 to pull rod 121 and attached plate 122 to the right, plugging subscriber A's jack 90 123 to the bus bars.

We have now directly connected together the jacks of subscribers A and B via the bus bars 110.

The next objective is to raise the bus bars 95 and attached jacks to an out of the way position so that another pair of subscribers may be plugged to another bus bar set. For this purpose, the bus bar elevator is provided, shown to the right of Fig. 3. This consists of 100 a pair of belts or chains 124, and 125 passing around pulleys 126, and 127. A power friction pulley 128 rubs against pulley 129 which is attached to pulley 126 tending at all times 105 to raise the left side of the belts upward. Attached horizontally between belts 124 and 125 are bus bar sets similar to 110 and equally spaced all around the outer edge of the belts.

Ringer 130 is shown wired to brushes which 110 bear on slip rings 131 and supply ringing current via wires 132 and 133 to the outer bus bars of 110.

Battery 134 supplies direct current to slip 115 rings 135. From one of these slip rings leads wire 137 to an inner bus bar of 110 and in this line is impedance coil 136. From the other slip ring leads impedance coil 138 and wire 139 to switch 140 and clamping magnet 141. The other terminal of magnet 141 is connected 120 to the lower inside bus bar of 110. It will be noted that the upper and lower bars of 110 are pivoted, and that the lower bars are attached to a lever arm 142 held lightly in a horizontal position by a tension spring. Lines 143 and 144 lead from inner battery 125 clips of subscriber A's jack 123. Lines 145 and 146 lead from the outer clips.

When jack 123 plugs into the bus bars 110, battery 134 is looped to subscriber A. Starting with battery 134, this circuit goes thru 130

impedances 136 and 138, wires 137 and 139, magnet 141 and the inside bars 110, inside clips of 123, wires 143 and 144 to subscriber A's ringer switch, Fig. 1. Line 143 goes to magnet 147 thru to lug 25 on the switch. Line 144 goes direct to lug 26. Blade 9 is in contact with lug 25, and blade 10 in contact with lug 26, being held there by magnet 17. Therefore, a loop is completed from battery 134 to lines 6 and 7 to subscriber A.

Magnet 147, being in the circuit, is energized and pulls core 27 and switch blades further down on lugs 25 and 26, breaking contact with lugs 14 and 15. This disconnection breaks the loop on lines 18 and 20, de-energizing magnets 24, 30 and 69, so that roll 34 falls away from the ratchets allowing them to drop back by gravity to their neutral position. Also switch 70 drops out, and subscriber A's re-

20 cording unit is restored to normal.

Referring again to Fig. 3,—magnet 141 is energized by the loop from battery 134 to subscriber A. It therefore draws down arm 142 thus clamping the middle clip of the two jacks 25 104 and 123 tightly between the upper and lower bus bars of 110. At the same time, magnet 141 draws up switch 140 which makes contact with lug 148 mounted on the same block. Lug 148 makes sliding contact with stationary spring 149 which connects via wire 150 to ratchet-wheel magnet 151 whose other terminal goes via wire 152 to the other side of battery 134. Magnet 151 is thus energized, and draws pawl 153 to the right. This allows 30 ratchet wheel 154 to turn clockwise one-half notch until caught by the lower tooth of pawl 153. At this stage the bus bars 110 and belts 124 and 125 have moved upward so that lug 148 has broken connection with spring 149. 40 This breaks the current thru magnet 151 allowing spring 155 to restore the pawl to normal, and the ratchet wheel 154 to turn one-half notch more in a clockwise direction.

This action brings bars 110 to a clear out 45 of the way position and also brings a lower set of bus bars into the exact position formally occupied by bars 110 on line with the bank of jacks, and ready for a new plugging connection.

50 The throwing out of switch 70 of subscriber A, Fig. 1 has also de-energized plugging solenoids 86, 87 and 88, and key magnet 111 so that jack units *a* and *b* are back to normal except that the jacks themselves 104 and 123 are 55 clamped in bus bars 110 and raised one step or notch higher. The jacks have risen vertically thru the horizontal spring rings of the jack rods. All the main parts of the system are restored to normal now, and subscriber A 60 is directly connected to subscriber B's line.

Now subscriber B is being rung. The ringer 130 is electrically connected at all times via wires 132 and 133 to the outside bus bars of 110. This puts ringing voltage on the 65 outside clips of A's jack 123 and B's jack 104.

This voltage is impressed on A's lines 145 and 146 which are open ended at terminals 11 and 12 on account of the ringer switch being held down by magnet 147. Therefore this ringing voltage does not directly affect A's receiver. 70

Tracing the ringing current in B's circuit, Fig. 2, we find it goes via lines 108 and 109 to terminals 156 and 157 on B's ringer switch. The blades 158 and 159 are held by spring 160 against terminals 156 and 157. Therefore, 75 ringing current passes via these blades thru line wires 161 and 162 to subscriber B's local phone set. Here, the ringing current goes thru dial switch 163, condenser 164, bell 165 and to the other line, thus making a circuit 80 and ringing the bell 165.

While subscriber B's bell is ringing, subscriber A hears a buzzing in his own receiver to let him know that B is being called. This is accomplished by employing a condenser and resistance in series, attached on each side of the ringer switch blades as shown by 166 and 167. The ringer voltage from terminal 156 goes thru blade 158, condenser and resistance 166, thru lug 168, magnet 170 to line 106. From terminal 157, the ringer voltage is impressed thru blade 159, condenser and resistance 167, and lug 169 to line 107. Tracing lines 106 and 107 to Fig. 3 these lines come to the center clips of B's jack 104 which are in contact with center bus bars 110. The center bars contact with center clips of A's jack 123 thus carrying the ringing voltage to lines 143 and 144. 95

Tracing these lines to Fig. 1, we find they terminate on lugs 25 and 26. Blades 9 and 10 are held in contact with these lugs so that the ringing current passes thru lines 6 and 7 and thru subscriber A's receiver 1, making a buzz and indicating to him that subscriber B is 100 being rung.

Referring to Fig. 2. Subscriber B, hearing the ringing of his bell, picks up receiver 171, raising hook switch 172. This makes a direct current loop from battery 19 via lines 173 and 174 magnet 175, lugs 176 and 177, blades 158 and 159, wires 161 and 162 thru dial switch 163, transmitter 178, switch 172, inductance 179 back to line 161. 110

Magnet or solenoid 175 thus energized, pulls down core 180 making blades 158 and 159 contact with lugs 168 and 169 respectively. This contact makes a loop with battery 134, Fig. 3 via lines 106 and 107, energizing solenoid 170 which pulls core 180 still further down and disconnects the blades 158 and 159 from lugs 176 and 177 breaking battery 19 loop to subscriber B. 120

The pulling down of which switch blades 158 and 159 has also broken contact with terminals 156 and 157, thus disconnecting subscriber B directly and subscriber A indirectly from the ringer. 125

The direct connection of subscriber A with subscriber B has now been accomplished. 130

They can communicate for an indefinite length of time and are not using up expensive apparatus during their "holding time". During this "holding time" other subscribers' 5 connections are being made by the jack plugging machine. Meanwhile the bus bars are rising a notch at a time and carrying the jacks with them.

Let us now assume that subscriber B hangs 10 up his receiver. This breaks the loop, and throws up his ringer-switch back to normal. Then subscriber A hangs up. This breaks the current in wires 143 and 144 and de-energizes magnet 141, allowing lever 142 to 15 raise, unclamping bus-bars 110, and allowing A and B's jacks 123 and 104 to fall out and drop back in to the jack rings, ready for another connection.

Thus we have traced thru one complete call 20 between subscriber A and B. It is obvious that since B's equipment is a duplicate of A's, the call could be reversed with B calling up and making a connection with A. Also it is evident with this key system that 25 a large number of subscribers can easily and quickly make connections with each other.

In Fig. 3 it will be noticed that bus bars 30 110 as they rise upward on the elevator belts will finally pass over the top of pulley 126 and go down the opposite side and eventually return under pulley 127 to rise up again.

Let us assume that it takes an average 35 during the busy hour, of a period of say one-half hour for the bus bars 110 to rise from a position opposite the jacks to the highest vertical position before making the turn over pulley 126. Let us also assume that two subscribers' jacks have been connected to this bus 40 bar and the subscribers have been conversing for the one-half hour period. It is quite obvious that it would not do for the jacks to be carried over the pulley with the bars. Therefore a safety device could readily be 45 provided which would trip out the jacks as they reached the highest vertical position of the bars. This device would limit the subscribers to a one-half hour "holding time" during the maximum busy hour of the day.

50 A telephone exchange operating with the above method of machine switching can be compared in certain respects to a safe-deposit box system in a bank. In the bank, each customer has an individually numbered safe deposit box and an individual key. Two keys are required to open any box, the customer's key and the bank attendant's key. The attendant may be likened to the calling subscriber in a telephone exchange, and a bank 55 customer likened to a called subscriber. The bank attendant inserts his key and the customer's key into the lock of the numbered box and opens the box. In this telephone exchange, the calling subscriber raises his 60 receiver hook (inserts his key), dials the num- 65

ber of the subscriber to be called (inserts the customer's key), and accomplishes a telephone connection or opens up communication (opens the safe deposit box). The keys for opening the bank boxes are flat steel pieces having lugs and depressions cut out of one side and are very similar in appearance and function to the individual jack key pieces of this machine switching system. In its essentials, therefore, this system can well be called 70 the "key system of machine switching".

A very important point to be considered in this invention is that in a single exchange office, say of 10,000 lines, there is no multiplying of subscribers' lines required, thus saving 80 an enormous amount of wiring and also repair expense due to faulty contacts, etc.

From previous description, it is seen that the subscribers' calls are stored up individually and released in turn upon the line connecting machine shown in the drawings. In a single machine, only one pair of subscribers can be connected at one time. It might seem at first thought, therefore, that in a 10,000 line exchange office, one such machine 85 could not take care of the telephone traffic by making only one connection at a time. However, the efficiency of this line connecting machine varies directly with its speed of operation. As its members are all electro-magnetically operated, which action is almost instantaneous, there is good reason for assuming that at least an average of two connections per second could readily be made by 90 this machine. There being 3600 seconds in an hour, then 7200 connections per hour could be made, which is more than ample for a 95 10,000 line office.

It would seem quite possible to have a 20,000 or 30,000 line office with this system, 100 should it be found necessary. Two switching machines could be used in such an office, all the called lines represented in each machine, but one-half the calling lines in one machine, and the other half in the other machine. This 105 arrangement is similar to the arrangement of a multiple switch-board. In a large city where, on account of economy in wiring, it is necessary to have local switching offices in the exchange and a trunking system, it will 110 be found that this key system adapts itself readily to trunking.

While I have shown and described the preferred embodiment of my invention, I wish 115 it to be understood that I do not confine myself to the precise details of the construction herein set forth, by way of illustration, as it is apparent that many changes and variations may be made therein, by those skilled in the art, without departing or exceeding the scope 120 of the appended claims.

I claim:

1. In a machine for connecting the calling and called lines of a telephone system, line 125 jack members keyed to correspond to the line 130

- numbers, digit members retaining the keyed line members, connective means opposing the line jack members, means to withdraw the digit members by the calling line, releasing the called line jack upon the connective means, means to release the calling line jack upon the connective means by the calling line, and means to ring the called line.
2. In a switching machine for connecting electrically the calling and called lines of a numbered line system, a line jack for each line, a bank of jack-holding members each equipped with a key-piece formed to correspond to its line number, a bank of movable digit rods bearing against the key pieces, each rod representing a digit of the numbers of the system, a movable battery bus bar bank for electrically connecting and holding any two line-jacks and situated opposing the bank of line-jacks, electro-magnets for operating the digit rods releasing the keyed jack holder and plugging the called line-jack to the battery bus bar set, an individual electro-magnet for releasing the calling keyed jack-holder and plugging the calling line-jack to the battery bus bar set, electro-magnetic means to step the jack-connected bus bar set and bring the next bus bar set to oppose the line of jacks, means to ring the called line, and means to restore jacks to normal on completion of call.
3. In a number recording mechanism of a machine switching system for telephone exchanges, a set of digit bus bars for each set of digits of the numbers of the exchange, said bus bars individually electrically connected to corresponding electro-magnets actuating digit rods in the central switching machine, a ratchet contact rod for each set of digits making sliding contact with corresponding set of digit bus bars, a friction power roll for raising ratchets into contact with digit bus bars, an electro-magnet and pawl mechanism for controlling the rise of each ratchet rod, said electro-magnet being actuated by pulsating current from a subscriber's number sending device, an electro-magnet in the subscriber's loop circuit actuating an idle roll which applies friction power roll to ratchet digit rods, a set of control lugs, each connected to a corresponding digit ratchet magnet a control ratchet rod making sliding contact with control lugs connected to the subscriber's loop circuit line and raisable by action of power and idler rolls, an electromagnet and pawl for controlling the rise of the control ratchet rod, said electromagnet receiving current from the secondary of a transformer whose primary is in the subscriber's loop circuit, an additional control lug in the above lug set electrically connected to a magnet for operating a jack magnet switch, a jack magnet switch for placing voltage upon digit ratchet rods and calling subscriber's individual jack magnet, and for placing voltage upon a hold-back line to keep other subscribers' jack magnet switches from throwing in.
4. In a telephone system, a subscriber's line ringer switch normally connected to open ringer lines and recording mechanism, magnetic means in said switch to disconnect the subscriber's line from ringer lines, and connect the subscriber's line to open jack lines when the subscriber's loop is made, electro-magnetic means in said switch to disconnect the subscriber's line from the recording mechanism when the jack line circuit is made, and means to restore the switch to normal when the subscriber's loop is broken.
5. In a machine switching system for telephone exchanges; individual means at the switching station for automatically recording the numbers dialed by the subscriber on a calling line, means to impress said called numbers upon a central switching machine, a switching machine for connecting the calling and called lines of the exchange, said switching machine comprising—line jack members keyed to correspond to the line numbers, digit members retaining the keyed line members, connective means opposing the line jack members, means to withdraw the digit members by the calling line, releasing the called line jack upon the connective means, means to release the calling line jack upon the connective means by the calling line, and means to ring the called line.
6. In a machine switching system for telephone exchanges; individual means at the switching station for automatically recording the numbers dialed by the subscriber on a calling line, means to impress said called numbers upon a central switching machine, a switching machine for connecting the calling and called lines of the exchange, said switching machine comprising—a line jack for each line, a bank of jack-holding members each equipped with a key-piece formed to correspond to its line number, a bank of movable digit rods bearing against the key pieces, each rod representing a digit of the numbers of the system, a movable battery bus bar bank for electrically connecting and holding any two line-jacks and situated opposing the bank of line-jacks, electro-magnets for operating the digit rods releasing the keyed jack holder and plugging the called line-jack to the battery bus bar set, an individual electro-magnet for releasing the calling keyed jack-holder and plugging the calling line-jack to the battery bus bar set, electro-magnetic means to step the jack-connected bus bar set and bring the next bus bar set to oppose the line of jacks, means to ring the called line, and means to restore the jacks to normal on completion of the call.
7. In the number recording mechanism of a telephone system, a set of digit bus bars for

each set of digits of the numbers, electrically connected to corresponding digit member magnets in the line connecting machine, a ratchet contact rod for each set of digits making sliding contact with corresponding set of digit bus bars, a power driven friction roll with suitable operating means to step ratchets

relative to digit bus bars by calling line, automatic means to apply calling line to operate stepping means of each ratchet consecutively in order of digits called, means to apply voltage to ratchets upon recording of numbers.

CLYDE F. McCANN.
